UNITED STATES PATENT OFFICE.

DAVID FOYER, OF DOVER, NEW HAMPSHIRE, ASSIGNOR TO ABRAHAM FOLSOM & SON, OF BOSTON, MASSACHUSETTS.

DESIGN FOR A FLOOR-CLOTH PATTERN.

Specification forming part of Design No. 1,677, dated December 9, 1862.

To all whom it may concern:

Be it known that I, DAVID FOYER, (an alien, having resided in the United States one year and made oath of intention to become a citizen thereof,) have invented or produced a new and useful Design to be Imprinted or otherwise Fixed on or in a Floor-Cloth or other Material, and do hereby declare the said design to be duly represented in the accompanying drawing.

The design in question consists, first, of an octagonal central panel A, surrounded by four smaller and semi-square panels B, within each of which there is a semi-cross arranged diagonally and underlaid by two semi-squares, colored in different tints, the said semi-cross being overlaid by one semi-square or right-angled triangle arranged between its four arms, as shown in the drawing, and the said

square panels being disposed at equal distances apart; second, between each two of the square panels and abutting against them and one side of the central panel is a quarter of an octagonal panel C, of different color and ornamented, as shown in the drawing; third, a flower piece D, surrounded by an octagonal belt E of stars in the main or central panel.

The drawing exhibits the above design in repetition as it is usually imprinted on a piece of floor-cloth or other material.

I claim—

The said design as my invention or production.

DAVID FOYER.
